UNITED STATES PATENT OFFICE

OLA L. BERBY, OF DULUTH, MINNESOTA, ASSIGNOR TO CLYDE IRON WORKS, OF DULUTH,
MINNESOTA, A CORPORATION OF MAINE

SAFETY DEVICE FOR HOISTING ENGINES

Application filed December 17, 1929. Serial No. 414,796.

This invention, relating as indicated to safety devices for hoisting engines, has specific reference to a means whereby the winding spool on which the hoisting cable is wound is automatically and substantially braked to obviate any accidental dropping of the suspended load.

Hoisting mechanisms as commonly employed, for example, in hoisting building material from the ground level to the upper levels of a building in the course of construction, are provided with no means other than the manual control of the operator for preventing the accidental falling of the suspended load, whether such load be an elevator carriage or a heavy structural steel member. In the construction of a hoisting unit of the type commonly employed the winding spool upon which the hoisting cable is wound is provided with a brake drum, on which is mounted the common type of brake band. This brake is actuated and controlled by a foot or hand lever which is manipulated by the operator of the hoist. After the driving means has been disconnected from the winding spool the load is normally held in elevated position by the application of the above mentioned brake and the load, consequently, is held suspended only so long as the operator maintains the application of the brake. The brake by which the load or elevator carriage is held in position is usually the same brake by which the descent of the carriage or hoisted material is regulated.

With the confusion necessarily incident to building construction and the many distractions which are present in the neighborhood of the hoisting mechanism operator, there are numerous possibilities for such operator becoming confused and releasing the brake with the resulting precipitation of the suspended loads and injury to persons in the vicinity where the load is dropped. A further source of danger is the element of carelessness present in the manner in which the hoisting mechanism is controlled by certain types of operators.

It is the purpose of my invention to provide a safety means for hoisting mechanism whereby any accidental dropping of the sus-

pended load is entirely obviated. It is a further object of my invention to provide a safety device for hoisting mechanism which shall be operable at all times and can in no way be impaired by any careless or unpremeditated act on the part of the operator. Other objects of my invention will be apparent as the description proceeds.

To the accomplishment of the foregoing and related ends, said invention, then, consists of the means hereinafter fully described and particularly pointed out in the claims; the annexed drawings and the following description setting forth in detail certain mechanism embodying the invention, such disclosed means constituting, however, but one of various mechanical forms in which the principle of the invention may be used.

In said annexed drawings:—

Fig. 1 is a plan view of a single drum hoisting mechanism comprising my invention showing in association therewith the mechanism comprising my invention; Fig. 2 is a side elevation of the mechanism illustrated in Fig. 1; and Fig. 3 is a fragmentary broken sectional view of the mechanism illustrated in Fig. 2 taken on the plane substantially indicated by the line 3—3.

Referring more specifically to the drawings and more especially to Fig. 1, the hoisting mechanism here shown consists of a supporting frame structure having side frame members 1 and 2, cross members 3 and 4 and a sill 5 upon which the hoisting mechanism is mounted. Extending transversely of the side frame members 1 and 2 is the shaft 6, which is revolvably supported by bearings 7 and 8, respectively mounted on the members 1 and 2. Positioned adjacent to, and parallel with, the shaft 6 is a driven shaft 9 which is revolvably supported by the bearings 10 and 11 on the side frame members 1 and 2, respectively. The side frame members 1 and 2 are here shown supporting a suitable prime mover, here shown as an internal combustion engine 12 which has a crank shaft 13 extending therefrom, to which is rigidly secured the driving means 14. The driving means 14 has intercom-

munication with a pulley 15 radially mounted on the shaft 9 by means of the flexible driving means 16. The shaft 9 has rigidly secured thereto the pinion 17 which is adapted to mesh with the gear 18 rigidly secured to the shaft 6. The shaft 6 has terminally mounted thereon a winch head 19, and intermediately of the side frame members 1 and 2 coaxially supports the winding spool 20. Driving communication is established between the winding spool 20 and the driving gear 18 by means of the thrust screw 21 acting through thrust nut 22 to axially move the winding spool 20 into communication with the friction blocks 23 so that upon rotation of the gear 18 the winding spool 20 will be likewise rotated. The thrust screw 21 is actuated by the control lever 24, which has its terminal portion 25 formed into a handle for the hand of the operator.

The winding spool 20 is provided with circumferential drums 26 and 27 which are adapted to receive the brake bands 28 and 29, the function of which will hereinafter be explained. Adjustment of the brake bands 28 and 29 is effected by the screws 30 and 31, respectively, which carry the adjusting lock nuts 32 and 33.

As most clearly shown in Fig. 2, the brake band 28 which, for purposes of convenience, will be termed the service brake, this being the brake which is normally manually controlled by the operator to regulate the descent of the suspended load, has its one terminal portion 34 bifurcated and secured to the plate 35, which is rigidly mounted on the base of the hoisting mechanism, by means of the pin 36. The opposite end 37 of the brake 28 is secured to the member 38 by means of the pin 39. The member 38 is rigidly secured to the shaft 40 which is revolvably supported by the bearings 41 and 42. The shaft 40 has rigidly secured thereto the arm 43 by means of the bifurcated end 44 thereof gripping the shaft 40, due to the action of the securing bolt 45. The arm 43 has a pad 46 secured to the terminal portion thereof, which pad is adapted to receive the foot of the operator. It will be noted that the downward movement of the arm 43, which is effected by pressure of the operator's foot on the pad 46 will cause a clockwise rotation of the shaft 40 and thereby effect a tightening of the service brake through a similar rotation of the member 38.

Positioned transversely of the side frame members 1 and 2, and suitably journaled therein is a shaft 47 which is rigidly secured to the member 48 which, through the pin 49, secures one end 50 of the safety brake 29. The opposite end of the safety brake 29 is secured to a plate similar to plate 35 by means of a pin similar to pin 36. The position of these securing members for this end

of the safety brake is directly behind the securing members for the similar end of the service brake, as shown in Fig. 2 and therefore is described in the above matter.

The winding spool 20 has rigidly secured thereto a pinion 51 which is adapted to intermesh with a gear 52. The gear 52 is loosely mounted on a shaft 53 and restrained against axial movement thereon in one direction by means of the nut 54. The shaft 53 is journaled in the bearing block 55 supported by the bracket 56 secured to the side of the frame of the hoisting mechanism. The bearing block 55 has its terminal portion 57 formed with steep preferably right-hand threads and has a circular aperture 58 coaxially formed therein. Positioned within the circular aperture 58 is a compression spring 59 adapted to bear against the circumferential flange 60 formed on the shaft 53. The relatively steep threads on the member 57 are engaged by similar threads 61 formed in the thrust cap 62, which has centrally positioned therein a thrust pin 63 which is locked in position by means of the nut 64.

The hub 65 of the gear 52 has revolvably and slidably mounted thereon the pinion 66 which has a circumferential axially extending flange 67 formed integral therewith. The flange 67 carries friction facing 68 adapted to contact with the web of the gear 52. The shaft 47 has rigidly secured thereto the toothed segment 69 which is adapted to mesh with the pinion 66.

The thrust cap 62 has a projecting element 70 formed integrally therewith which terminally carries a revolvably frictionless roller 71 on the pin 72. Revolvably secured in the frame of the hoisting mechanism is a shaft 73 which has terminally secured thereto a control handle 74, and which has likewise rigidly secured thereto a cam element 75. The control handle 74 has a projection 76 formed integrally therewith, which is adapted to oscillatably support a rod 77 by a pin 78. The rod 77 has coaxially mounted thereon a spring 79 which is axially restrained by means of the nut 80 and the plate 81 secured to the side frame member 2, through which plate the rod 77 passes. The rod 77 has its lower end 82 formed with a substantially longitudinal slot 83 therein, said slot adapted to receive a pin 84 carried by the arm 85 which is rigidly secured to the shaft 40.

The operation of the device, so far as the establishment of driving connection between the winding spool 20 and the driving gear 18 is concerned, has been hereinbefore fully explained. Likewise, the manipulation of the service brake, by means of which the descent of the suspended load is regulated, through the action of the arm 43, has also

been explained. The operation of the safety brake will now be briefly outlined.

When the winding spool 20 is rotating in the direction indicated by the arrow in Fig. 2, which is the direction necessary to wind the hoisting cable thereon, the pinion 51, which is rigidly mounted on the winding spool 20, will rotate in a counter-clockwise direction, imparting a clockwise rotation to the gear 52, as illustrated in Fig. 2. The action of the spring 59 is to force the shaft 53 to the left, as shown in Fig. 3, thereby maintaining frictional engagement between the flange 67 and the web of the gear 52, through the friction facing 68. Rotation of the gear 52 will therefore cause a like rotation of the pinion 66 which will cause a counter-clockwise rotation of the toothed segment 69, as illustrated in Fig. 2. The toothed segment 69 will rotate in a counter-clockwise direction until it strikes a stop 86, whereupon the pinion 66 will be held stationary and the gear 52 permitted to rotate against the friction of the facing 68. This counter-clockwise rotation of the toothed segment 69 will cause a release of the safety brake by a like rotation of the element 48 which secures the terminal portion 50 of the brake. Should by any chance the winding spool 20 be permitted to freely rotate in a clockwise direction, thereby causing a dropping of the suspended load, the direction of rotation of the gears comprising the above described gear train would be reversed and the toothed segment 69 caused to rotate in a clockwise direction, which would immediately apply the safety brake.

For the efficient operation of a safety brake, such brake should be so actuated that a release thereof is effected upon application of the service brake by the operator of the hoisting mechanism. This release of the safety brake, upon application of the service brake, is accomplished by the rod 77 being pulled downwardly upon depressing the arm 43, which rod will cause a clockwise rotation of the cam 75. The cam 75, upon being rotated, will, through the frictionless roller 71, cause a clockwise rotation of the thrust cap 62 which, through the thrust pin 63, will move the shaft 53 to the right, as shown in Fig. 3, against the pressure of the compression spring 59. This movement to the right of the shaft 53 will effect a disengagement of the friction facing 68 and the web of the gear 52, and the spring 87 will thereupon return the toothed segment to the dotted line position shown in Fig. 2, thereby releasing the safety brake.

It is a further advantage to the efficient operation of a hoisting mechanism that a simultaneous application of both brakes be possible to securely maintain a hoisted load of unusual proportions in elevated position.

If, after the service brake has been applied

by depressing the lever 43 which, as before explained, will automatically release the safety brake, the operator should be desirous to also cause an application of the safety brake, a clockwise rotation of the cam element 75, by means of the handle 74, until the frictionless roller 71 rests on the flat face of the cam opposite to that on which it is shown resting in Fig. 2, this position of the roller will permit the full effect of the spring 59 on the shaft 53 which, as hereinbefore explained, will effect an application of the safety brake.

It will be noted in connection with the above described mechanism that a positive means is provided for preventing the accidental dropping of a suspended load, such device having the necessary requisites of a safety device in that any unpremeditated or careless act on the part of the operator can in no way impair the efficiency of its operation.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a hoisting mechanism, the combination with a winding spool, a safety brake associated with said spool, frictionally engaged means for applying said brake upon unwinding rotation of said spool, resilient means for normally maintaining said frictional engagement, a service brake for said spool, means for releasing said frictional engagement, upon application of said service brake, and independently operable means adapted to effect said frictional engagement during the application of said service brake.

2. In a hoisting mechanism, the combination with a winding spool, a safety brake associated with said spool, frictionally engaged means for applying said brake upon unwinding rotation of said spool, resilient means for normally maintaining said frictional engagement, a service brake for said spool, means for releasing said frictional engagement upon application of said service brake, independently operable means adapted to effect said frictional engagement during the application of said service brake, and means freeing said safety brake upon release of said frictional engagement.

3. In a hoisting mechanism, the combination with a winding spool mounted on a shaft, a safety brake associated with said spool, a pinion mounted on said shaft, a second shaft slidably and revolvably mounted adjacent to and parallel with said spool carrying shaft, a gear mounted on said shaft intermeshing with said pinion, a second gear

mounted on said last-named shaft adapted to frictionally engage said last-named gear, means associated with said second gear for actuating said safety brake, and resilient means for normally maintaining said frictional engagement.

4. In a hoisting mechanism, the combination with a winding spool mounted on a shaft, a safety brake associated with said spool, a pinion mounted on said shaft, a second shaft slidably and revolvably mounted adjacent to and parallel with said spool carrying shaft, a gear mounted on said shaft internemeshing with said pinion, a second gear mounted on said last-named shaft adapted to frictionally engage said last-named gear, means associated with said second gear for actuating said safety brake, resilient means for normally maintaining said frictional engagement, a thrust screw for effecting disengagement of said frictional engagement,

means for actuating said thrust screw upon application of the service brake of said spool, independently operable means for actuating said thrust screw to effect said frictional engagement during the application of said service brake, and means for freeing said safety brake upon disengagement of said frictional engagement.

5. In a hoisting mechanism, the combination of a winding spool, a service brake for said spool, means for actuating said service brake, a safety brake for said spool, means including relatively movable frictionally engaged means energized by unwinding rotation of said spool and deenergized by actuation of said service brake for actuating said safety brake, and means for energizing said safety brake during application of said service brake.
